UNITED STATES PATENT OFFICE

2,476,691

STITCH PICKING MACHINE

George C. Bennett, West Huntsville, Ala.

Application August 10, 1945, Serial No. 610,055

10 Claims. (Cl. 12—17)

1 My present invention relates to improvements in thread pickers or removers and is particularly designated to remove the threads left in a shoe welt after a sole has been removed prior to stitching a new sole to the welt. More particularly, it is my purpose to provide a resilient clamping means for holding the welt of a shoe in position for removal of threads and movably supporting the welt in proximity with the picking so that each thread remaining therein will be picked or removed quickly, conveniently and with little labor. Heretofore, it has been the practice to use an awl or sharp hand tools for removing remaining threads from a welt after a worn sole has been removed. In removing the worn sole, a sharp knife is usually inserted between the worn sole and the welt to cut the threads or stitching. This leaves parts and vestiges of threads in the welt, and if left in the welt, they are unsightly and undesirable when a new sole is stitched to the welt. The remaining parts and vestiges of the thread in the welt are usually inverted U-shaped, and the operation of picking them out by hand is laborious and time consuming. My machine accomplishes simply, quickly and without appreciable labor the removal of threads from a welt, and there are no fragile or intricate parts likely to become deranged or broken or inapt for use, and the machine is simple in construction and practical in operation.

Other and equally important objects and advantages of my invention will be apparent from the following description and drawings, and it is pointed out that changes in form, size, shape, materials, and construction and arrangement of parts is permissible and within the purview of my broad inventive concept and the scope of the appended claims.

In the drawings wherein I have illustrated a preferred form of my invention:

Figure 1 is a vertical front elevation;

Figure 2 is a vertical side elevation;

Figure 3 is a section on the line 3—3 of Figure 1;

Figure 4 is a section through the driving mechanism for the brush; the thread removing wheel and the eccentric operating mechanism for the thread picker;

Figure 5 is a section on the line 5—5 of Figure 3;

Figure 6 is a perspective view of one of my thread picker blades;

Figure 7 is a side view of the cam block for returning the thread picker blades to passive position;

2 Figure 8 is a front view of the cam block shown in Figure 7;

Figure 9 is a detail of the worm drive and eccentric connection to the yoke of the thread picker blade actuating rod;

Figure 10 is a section on the line 10—10 of Figure 1, and

Figure 11 is a perspective view of a modified form of thread picker blade.

In the drawings wherein like characters of reference are used to designate like or similar parts:

The numeral 1 designates the supporting legs of my device which are suitably attached to a convenient base. There are preferably four legs 15 transversely reinforced and connected by a platform 2 formed integral with the legs at the medial portion thereof. The legs have integrally formed thereon above and in vertical relation with the platform 2 the end plates 3, and a handle and guard 4 is connected with the end plates at the upper ends thereof.

Formed on one end plate 3 above the platform 2 is a bearing 5 for the stub shaft 6 of a driven gear 7 having a hand operating handle 8 formed thereon on the opposite side of the gears by which it is rotated. Mounted on a table 9 parallel with and above the platform 2 and formed integral with the end plate 3 are the upstanding bearings 10 between which is journaled a shaft 11 carrying a worm gear 12 at the central portion thereof and a driven pinion 13 on one end thereof which is in mesh with the drive gear 7. The worm gear 12 is in mesh with a gear 14 which is a double gear having an annular toothed area 15 inwardly of the gear teeth thereon which is in mesh with a gear 16 on a shaft 17 which is journaled at right angles to the gear 14. The gear 14 is carried on shaft 18 mounted in the guard 4 in parallel relation to shaft 17, and shaft 11 has fixed thereto inwardly of the bearings 10 eccentricities 19.

Shaft 18 is journaled at one end in a standard end plate 3 and carries a slotted picker blade roller 20, with uniformly spaced slots 21 in the periphery thereof—see Figure 5—to slidably receive thread picker blades 22 therein—see Figure 6. At the forward end of shaft 18 is attached by a screw 23 a toothed sole engaging pressure disc 24 which is prevented from independent rotation with respect to the shaft by a locking screw 25.

50 A sleeve 26 is mounted on the disc 24 and holds the picker blades slidably in place in the slots 21. Extending through the bearing 27, Figure 3, on the plate 3 above the sleeve 26 is the opposite end of the shaft 17 which carries a brush 28—see Figure 1. The brush has a guard 29 mounted on the

bearing 27. Consequently, it will be seen that on turning the handle 8, the drive gear 7 is rotated and the worm gear 12, also the double gear 14 which rotates shaft 11 and pinion gear 16 on shaft 11 to rotate the slotted picker blade roller 20 and the brush 28.

A block 30 on the bearing 27 on the plate 3 has a cam face 31—see Figures 7 and 8—which engages the shoulders 32 on the picker blades 22 to normally urge the picker blades to a retracted position back of the front end of the slotted picker blade roller. Each picker blade is flat and has an elongated shank 33 and a sharpened point 34, or as shown in Figure 11—the picker blades may have sharpened knife like ends 35 for cutting threads. The blocks comprise bodies 36 cylindrical part 37 for the bearing 27 as well as the cam face 31.

Engaging the eccentrics 19 on shaft 11 is the yoke 38 carried on the picker blade actuating rod 39. The rod is in two sections connected by a turnbuckle 40 and the threads of the section into the turnbuckle may be 24 threads to the inch and 28 threads to the inch, both right hand threads, or the difference between the threads may be more or less than the figures given depending on the differential desired in making fine adjustments of the length of the rod by means of the turnbuckle. The rod 39 extends through the plate 3 and has a slot 41 in the end opposite the threaded end which is engaged by a screw 42 to center the rod while permitting sliding movement in response to the rotation of the eccentrics, and the end of the rod has a blade like plunger which is timed to contact each picker blade 22 as it passes the end of the rod to move it forward on the slotted picker blade roller 20 to a point adjacent the toothed thread removing disc 24.

Slidably mounted in a bearing block 43 on the end 3 is a support 44 for the roller 45. The roller 45 has a flange 46 and is journalled as at 47 on the top of the support 44. The support is held in place by plates 45a and has a reduced rod-like extension 48 at its lower end about which is a spring 49. The spring 49 seats on the lower end of the support 44 and against a plate 50 through which the rod extends. The rod carries a nut 51 at its lower end, and the support 44 is normally urged upward by the spring. The plate 50 is slidably mounted in a slot 50a—see Figure 10—for limited sliding movement and is engaged by the cam end 52 of the adjusting lever 53. The lever 53 has a spring dog 54 and an operating handle 55 and upon movement of the same, the plate is adjusted upwardly or downwardly to adjust the tension of the spring 49. A hand lever 56 pivoted at 57 to the end 3 is pivotally connected as at 58 in a slot 58a in the support 44 to move the support down for the reason which will herein-after appear.

The flanged roller 45 is below and back of the toothed sole engaging pressure disc 24 and the welt of a shoe is placed on the roller 45 and the roller is moved by spring 49 to engage the welt between the roller 45 and the slotted picker blade roller 20 which places threads to be picked in line with the picker blades 22. Upon turning the gear 7 the rod 39 is reciprocated by eccentrics 19 to pass under loose threads which are extracted by the blades and picked off by the teeth of the slotted picker blade roller 20 whereupon the brush 28 brushes the threads from the slotted picker blade roller 20. The welt is released by pressing down on hand lever 56. The picker blades are re-

turned to passive position after a thread is picked by the cam face of block 30.

From the foregoing, it is believed that the operation and advantages of my invention will be apparent, but it is again emphasized that interpretation of its scope should only be conclusive when made in the light of the claims.

I claim:

1. A thread picking machine, comprising a supporting roller for the welt of a shoe and over which the welt is moved, a toothed sole engaging pressure disc mounted above the supporting roller against which the welt is held by the supporting roller, said supporting roller being mounted for vertical sliding movement, an adjustable spring tensioning means for pressing the supporting roller toward the toothed sole engaging pressure disc, to hold the welt therebetween, a slotted picker blade roller positioned rearwardly of the disc and in contact with the rotating brush, a plurality of thread picker blades slidably mounted in the slots, a reciprocating blade actuating rod engaging the blades in step-by-step sequence to pick the threads from the welt, and a rotating brush mounted above and in contact with the slotted picker blade roller to remove the threads from the blades after the threads have been picked from the welt.

2. The invention as defined in claim 1 wherein the supporting roller is flanged and the welt is held against the flange on the supporting roller.

3. The invention as defined in claim 1 wherein the supporting roller is journalled in a sliding block, a rod on the block, an adjustable plate, and a spring about the rod and engaging the block and plate to urge the roller toward the slotted picker blade roller, cam means for adjusting the plate, and a lever for moving the block against the tension of the spring.

4. The invention as defined in claim 1 wherein the slotted picker blade roller has a plurality of equally spaced peripheral slots in each of which a blade is mounted, a sleeve for holding the blades slidably in contact with the roller, and cam means for returning the blades to passive position after they have been moved to pick a thread.

5. The invention as defined in claim 1 wherein the picker blades are flat and have elongated bodies and end projections against which the cam blade returning block engages and the other ends of the blades having sharpened ends.

6. The invention as defined in claim 1 wherein the toothed sole engaging pressure disc is carried on the end of the slotted picker blade roller, and wherein the brush has a guard.

7. The invention as defined in claim 1 wherein the reciprocating picker blade actuating rod is sectional, a turnbuckle connecting the sections, the sections having right-handed threads of different pitch to affect precise adjustment in the length of the rod.

8. The invention as defined in claim 1 wherein the spring adjustment for the supporting roller has an adjusting lever with a cam element, and a latching dog to hold the lever in adjusted position.

9. A thread picker, comprising a picker blade carrying roller, slideable blades on said roller, a reciprocating actuating member for actuating the blades, a toothed sole engaging pressure disc, a rotary brush, the sole engaging pressure disc mounted on the blade carrying roller, a drive gear, a shaft carrying a pinion engaged by the drive gear to rotate the shaft, eccentrics on the shaft engaging the actuating member to reciprocate the member, a worm gear on the shaft, a double

gear having a shaft connection to the blade carrying roller and engaged by the worm, and a pinion on a shaft connection to the brush and engaging the second gear area of the double gear to be driven thereby.

10. The invention as defined in claim 9 wherein the connection between the rod and the eccentrics is a yoke having eccentric straps engaging the eccentrics, and wherein the gears and shafts are supported by a frame having end plates, platforms, and a handle.
